[57] ABSTRACT

A bathtub brush device having a motor operated rotatable cylindrical brush within the tub for cleaning and therapeutic massaging of a person lying in the bathtub, the brush being mounted on a rotatable shaft transversely disposed between the side inner walls of the bathtub. In one embodiment the brush is positionable to several heights within the tub, as well as along the length of the tub, so as to permit various massaging positions.

FIG. 14

BATHTUB BRUSH DEVICE

This invention relates to a motor operated bathtub brush device.

This invention relates to a cylindrical brush rotatably mounted within the tub to permit massaging of a person lying in the tub.

It is an object of this invention to provide a body cleaning device comprising a rotating brush for cleansing and massaging a person in a bathtub and means readily controlled by the person lying in the bathtub to operate the device.

Another object of this invention is to provide a device of the character described having means to easily disengage and engage the brush to facilitate cleaning of the brush or replacement thereof.

Another object of this invention is to provide a device of the character described comprising a carriage or rails movable longitudinally of the bathtub, and a brush carrying means pivoted to the carriage whereby the brush itself can be moved to various vertical and longitudinal positions to enable the person in the bathtub to clean different parts of the body.

Yet another object of this invention is provide a body cleansing device for a bathtub which is removably attached in position for use but which may be removed and stored easily.

Still another object of this invention is to provide a strong, rugged and durable device of the character described which shall be relatively inexpensive to manufacture and install, and which shall be easy to manipulate and practical and efficient to a high degree.

The above and other objects of the invention will later become apparent as the following description proceeds, are attained by the present invention, preferred embodiments of which have been illustrated, by way of example only, in the accompanying drawings, forming a part of this specification in which like characters are employed to designate like parts throughout the same, and wherein:

FIG. 1 is a perspective view of a brush embodying the invention, in a bathtub;

FIG. 2 is a sectional view of the brush device taken along line 2—2 of FIG. 1;

FIG. 3 is an enlarged sectional view of the means to allow removal of the brush from the bathtub, of FIG. 2;

FIG. 4 is a plan view of another embodiment of the invention installed in a bathtub;

FIG. 5 is a sectional view taken along line 5—5 of FIG. 4;

FIG. 6 is an enlarged sectional view taken along line 6—6 of FIG. 4;

FIG. 7 is a plan view of another embodiment of the invention installed in a bathtub;

FIG. 8 is a side elevational view of the embodiment of FIG. 7 with a portion of the bathtub cut away;

FIG. 9 is a sectional view taken along line 9—9 of FIG. 7;

FIG. 10 is an alternate embodiment of the means to remove the brush from the bathtub;

FIG. 11 is a plan view of still another embodiment of this invention;

FIG. 12 is a sectional view taken along line 12—12 of FIG. 11;

FIG. 13 is an enlarged sectional view of part of FIG. 12; and

FIG. 14 is a side elevational view of the embodiment of FIG. 11 with a portion of the bathtub cut away.

Referring now to FIGS. 1 and 2, there is shown a cylindrical brush 1 mounted by a shaft 2 which is slidably received in a pair of socket means 3a and 3b mounted on the side inner walls 4a and 4b, respectively of bathtub 4 and between the side outer walls 4c and 4d respectively. The bathtub comprises a pair of end walls 4e and 4f and a pair each of side inner and outer walls 4a and 4c and 4b and 4d respectively.

The cylindrical brush 1 comprises bristles 5 affixed to the peripheral surface 6a of hollow cylinder 6, the cylinder having axial end openings, 6b (only one shown) on each end 6c (only one shown), respectively thereof. The shaft 2 is fixedly held to the end openings of the cylinder 6 so that upon rotation of the shaft, the cylindrical brush is rotated therewith.

As stated the ends of the rotatable shaft, are held within socket means 3a and 3b. Socket means 3b comprises cup 7 the interior cup surface 7a thereof being in slidable relationship with one end of shaft 2. Inwardly of the cup is cover plate 31 with a central hole for receiving shaft 2. The outer cup portion 7b of cup 7 is attached to one end of a drive shaft 8, the other end of the drive shaft being coupled to a drive electric motor 9, said drive motor being electrically connected to a switch 10, the switch button 11 being mounted on the outer wall 4d of bathtub 4. The outer cylindrical portion 7c of cup 7 is attached to annular collar 12 which is rotatable within annular collar 13 by means of ball bearings 14. Said annular collar 12, annular collar 13, ball bearings 14, cup 7, shaft 8, motor 9, and switch 10 being arranged with housing 15 mounted through and between walls 4b and 4d, said housing 15 having an outwardly disposed flange 15a which is provided with four bolt holes 16 (typical) for receiving four bolts 17 (typical) in the respective holes.

Referring now to FIG. 2 and more specifically FIG. 3, there is shown socket means 3a which comprises a cup 18, having a partial spherically-shaped outer surface 18a and an internal tee-shaped interior 18b, the top part of the tee being an undercut. Fixedly mounted in the undercut of the internal tee-shaped portion 18b, is an outer annular collar 19 and rotatably mounted between annular collar 19 the inner surface of said outer and the outer surface of an inner annular collar 20, are ball bearings 21, so as to permit the inner annular collar 20 to freely rotate within the outer annular collar 19. The inner annular collar has a hole 22 coincident with its central axis, said hole 22 slidably receiving brush shaft 2.

The cup 18 is held in socket means 3a by a retaining member 23 having an internal level 24 for slidably fitting with the spherical surface 18a of the cup. Retaining cup 23 has external threads 25 which screws into internal threads 26 of housing 27; said housing 27 being disposed between bathtub walls 4a and 4c. Housed within said housing 27, between outer wall 4c and cup 18 is a spring 28 for urging cup 18 inwardly against bevelled surface 24. The housing 27 is attached to the inner wall 4a by means of four bolts 29 (typical) and said housing 27 is held in place at the outer wall 4c by cover plate 30.

Referring now to FIG. 3 there is shown the method for removing brush 1 from socket means 3a. To remove brush 1, said brush is pressed axially outwardly in the direction of socket means 3a; the shaft 2 forces partial

spherically-shaped cup 18 outwardly thereby compressing spring 28. In this manner the opposite end of shaft 2 is drawn inwardly clearing the outer face of cover plate 31. The entire brush 1 and shaft cross-sectional is then rotated upwardly and the end of shaft 2 withdrawn from partial spherically-shaped cup 18.

Referring to FIGS. 4, 5 and 6, there is shown another embodiment of the invention. Brush 101, similar in construction to aforesaid brush 1, is housed within bathtub 104, transversely disposed between inner walls 104a and 104b and outer walls 104c and 104d, respectively. Said cylindrical brush is mounted on axially rotatable shaft 102 so that said brush rotates with said shaft. The shaft 102 desirably has a square cross-sectional configuration.

The end of the shaft 102a, opposing wall 104b, is slidably received in the inner surface of an inner annular collar 103, the outer surface of said collar is grooved to receive ball bearings 105 (typical). And surrounding the ball bearings is an outer annular collar 106 with a groove on the inner surface of the outer annular collar 106 so as to retain the ball bearing therein. This ball bearing assembly is similar to other assemblies in this embodiment as well as other embodiments as will be pointed out hereinafter.

Fixedly attached to the outer surface of outer annular collar 106 is the lower end of a first vertical member 107 which is perpendicular disposed to shaft 102. The upper end of vertical member 107 is fixed attached to the outer surface of an outer annular collar 108 of a ball bearing assembly similar to the previously described ball bearing assembly; the components being an outer annular collar 108, ball bearings 110 (typical), and inner annular collar 109.

Slidably retained within the central hole of inner annular collar 109 is one end 111a of a support shaft 111, said support shaft being in parallel disposition to aforesaid brush shaft 102. The other end 111b of said support shaft 111 is centrally mounted at one end of motor M.

At the other end of motor M is a drive shaft 112 which is in parallel disposition with brush shaft 102, said drive shaft 112 the axis thereof being coincident with the axis of support shaft 111. Mounted on said drive shaft 112, between the end 112a thereof and motor M is a third ball bearing assembly similar to the aforesaid assemblies; having an outer annular collar 113, inner annular collar 114 and ball bearing 115 (typical). Fixedly attached to the outer surface of outer annular collar 113 is a depending second vertical member 116 which is in parallel disposition with aforesaid first vertical member 107. The lower end of vertical member 107 is fixedly attached to a fourth ball bearing assembly, similar to the aforesaid ball bearing assemblies and having outer annular collar 117, inner annular collar 118 and ball bearing 119 (typical).

Mounted within inner annular collar 118 is a rotatable connecting shaft 120 having on the inward end thereof a cup 121, the inner periphery of cup 121 slidably receives one end 102b of square brush shaft 102.

Mounted within the interior of cup 121 is a spring 122 for urging the shaft 102 inwardly so that the other end 102a of the shaft presses against retaining plate 123; mounted said plate 123 within the inner bore of inner annular collar 103.

Thusly, the brush 101 is in parallel disposition to shafts 111 and 112 and joined thereto through vertical members 116 and 107, respectively, and through the aforesaid four ball bearing assemblies. By this construction the brush may be manually positioned along an arcuate path, the radius of the arch being the length of the vertical members. In this manner the brush may be positioned by a person lying in the bathtub to several heights in the bathtub as is desired.

10 Referring again to FIG. 5, there is shown the end 112a of drive shaft 112 which shaft rotates with actuation of motor M. Mounted near the shaft end 112a is an upper pulley 124 having retained on the inner periphery of a central bore therein, an annular ring 125, 15 said ring 125 frictionally held to drive shaft 112. The peripheral groove of upper pulley 124 frictionally receives endless belt 126.

15 Referring again to FIG. 5 and more specifically to FIG. 6, there is shown the lower pulley 127, similarly constructed to the upper pulley 124, and having an inner annular ring 128, said ring frictionally receiving the aforesaid connecting shaft 120. The peripheral groove of the lower pulley frictionally receives the aforesaid endless belt 126 in a manner similar to that 25 as afore-described for the upper pulley 124.

20 By this manner of construction, the actuated motor M rotates drive shaft 112 causing rotation of upper pulley 124 thereby moving endless belt 126 which in turn translates its movement to lower pulley 127 which in turn causes rotation of connecting shaft 120 which in turn rotates shaft 102 thereby rotating cylindrical brush 101.

25 The top side walls 104e and 104f of bathtub 104 are provided with guide channels 150e, and 150f, respectively. The guide channels are pressingly held between walls W1 and W2 by turnbuckle means 151e and 151f, respectively. Rotatably housed within said channels 150e and 150f are two sets of roller-mounted parallel, spaced, support bars 152 and 153 said bars in parallel disposition to shaft 111, 112 and brush shaft 102; bar 152 having rollers 152a and 152b freely rotatable at the ends thereof, and bar 153 having rollers 153a and 153b freely rotatable at the ends thereof. The bars 152 and 153 per se do not rotate, but rotational bearing surfaces 154 (typical) at the ends thereof permit free rotation of the rollers 152a, 152b, 153a and 153b. The rollers upon rotation roll through and within aforesaid guide channels.

30 35 40 45 50 55 60 65 70 75 80 85 90 95 The support bars 152 and 153 are interconnectedly spaced by means of members 155 and 156; each of said members being affixed to one of said support bars. Member 156 is in the shape of a platform, and as such, serves as a platform for motor M which is mounted thereto.

By means of the construction described immediately hereinabove, a person lying in the bathtub can move the cylindrical brush 101 laterally, as shown by the double arrow in FIG. 4.

In operation, a person lying in the bathtub can adjust the cylindrical brush to any height at any lateral point in the bathtub, thereby permitting numerous positions in which the rotating cylindrical brush can contact any one of several parts of the body. For example, the legs may be positioned under the brush or draped over the brush. Also, the person in the bathtub may assume several postures, such as lying on the back, prostrate, or sitting, as desired, for brush massaging.

Referring now to FIGS. 7, 8 and 9, there is shown still another embodiment of this invention. In FIGS. 7 and 8 there is shown a cylindrical brush 201, similar to aforesaid brushes 1 and 101, transversely disposed in bathtub 204.

The drive means for rotating cylindrical brush 201 comprises a motor M-1, mounted below floor F and mounted outwardly of and below the outer wall 204a, by means of vertical plate P. The motor drive shaft 202 protrudes inwardly through outer wall 204a and outwardly of the outer surface of the corresponding inner wall 204b. Mounted at the end of drive shaft 202 is, lower pulley 205 having endless belt 206 frictionally held to the peripheral groove therein. Rewardly and upwardly of the lower pulley 205 is an upper pulley 207 of larger diameter than the lower pulley 205.

Endless belt 206 is of course frictionally and tautly held to the peripheral grooves of the lower and upper pulleys so as to translate motion therebetween. Both of the aforesaid pulleys are disposed between the outer surface of inner wall 204b and the opposed inner surface of outer wall 204a of the bathtub 204.

Projecting inwardly from the hub of upper pulley 207 is a rotatable cylindrical connecting shaft 208 having an axial square hole 208a therethrough. The connecting shaft protrudes through the inner wall 204b into the bathtub cavity and is rotatable within bushing 209, said bushing mounted in the inner wall and retained therein by cover plate 210, said cover plate fixedly mounted to the inner surface of the inner wall 204. The cover plate has a central bore 210a through which connecting shaft 208 slidably passes, thereby allowing the connecting shaft to freely rotate therein.

The square hole 208a of connecting shaft 208 slidably receives one end 211a of square brush shaft 211 being fixedly fitted into a central bore 201a at one end of cylinder 201b of brush 201.

Mounted within a central cylindrical bore 201c at the other end of cylinder 201b of brush 201, is a ball bearing assembly, similar to those ball bearing assemblies as aforesaid, and having an outer annular collar 212, an inner annular collar 213, and ball bearings 214 (typical). Slidably received within the inner surface of inner annular collar 213 is one end 215a of cylindrical shaft 215, the other end 215b of said cylindrical shaft 215 is fixedly mounted to plate 216, said plate 216 in turn being fixedly attached to the inner surface of inner bathtub wall 204c. In this manner the brush 201, driven by connecting shaft 208 in combination with brush shaft 211 is freely rotatably about cylindrical shaft 215.

Further, longitudinally disposed within the cylindrical hollow of cylinder 201b is a compression spring 217, said spring 217, the ends thereof pressing against ends 211b and 215a of shaft 211 and 215, respectively. By this construction, the brush 201 may be removed from the assembly by first moving the brush laterally in the direction of the wall 204c, thereby compressing spring 217, and clearing end 211a from the inward surface of plate 210. The brush may then be cleared of shaft 215 and removed from the bathtub.

Referring now specifically to FIG. 10, there is shown still a further embodiment of the invention. More specifically there is shown an alternative construction for removing a brush similar to that of FIGS. 7, 8 and 9 from the bathtub cavity. Cylindrical brush 301 comprises a hollow base cylinder 301a having circular

bore 301b and 301c at the respective ends thereof. Mounted with the hollow of base cylinder 301a at each of the ends 301b and 301c thereof are dowel members 302 and 303, respectively. Formed at each of the ends 5 of dowel member 303 are projecting shaft members 303a and 303b. Shaft member 303b projects inwardly in the hollow of cylinder 301a and member 303a projecting outwardly through central end bore 301c and into the inner receiving surface of a ball bearing assembly 304 (similar to previously described ball bearing assemblies). Ball bearing assembly 304 is fixedly housed within inner bathtub wall 305a. Formed at the ends of dowel member 302 are projecting shaft members 302a and 302b. Member 302a projects outwardly 15 through central bore 301b of cylinder 301a and into the inner receiving surface of a ball bearing assembly 306 (similar to previously described ball bearing assemblies). At the outer end of projecting shaft member 302a is an internal cup 307 of square configuration for slidably receiving square rotatable shaft 308, said shaft 308, the end other than the received end thereof being attached to the hub of a rotatable drive pulley 310.

Thusly the rotating pulley 310, rotates shaft 308 which in turn rotates projecting shaft member 302a 25 (employing ball bearing assembly 306 for rotation therewith) which in turn causes cylinder 301a to rotate, in turn rotating projecting shaft member 303a (employing ball bearing assembly 304 for rotation therewith).

30 Mounted within the hollow of cylinder 301a and disposed between opposed projecting shaft members 302b and 303b, is a compression spring 311. By this manner of construction the brush 301 may be removed from the bathtub by moving the brush in axial direction 35 toward inner wall 305a, thereby compressing spring 311, until the end of projecting shaft member 302a clears the inward surface of inner wall 305b. The other outwardly projecting shaft member 303a at the other end of cylinder 301a may then be cleared of the inner surface of inner wall 305a, thereby freeing the entire brush assembly for removal of the same from the bathtub cavity.

45 Referring to FIGS. 11, 12, 13 and 14, there is shown still another embodiment of the invention similar to that of FIGS. 4, 5, and 6. Brush 401, similar in construction to aforesaid brush is 1, and 101, is housed within bathtub 404, transversely disposed between inner walls 404a and 404b and outer walls 404c and 404d, respectively. Said cylindrical brush is mounted on axially rotatable shaft 402 so that said brush rotates with said shaft. The shaft 402 desirably has a square cross-sectional configuration.

50 The end of the shaft 402a, opposing wall 404b, is slidably received in the inner surface of an inner annular collar 403, the outer surface of said collar is grooved to receive ball bearings 405 (typical). And surrounding the ball bearings is an outer annular collar 406 with a groove on the inner surface of the outer annular collar 406 so as to retain the ball bearing therein. This ball bearing assembly is similar to other assemblies in this embodiment, as well as other embodiments as will be pointed out hereinafter.

55 Fixedly attached to the outer surface of outer annular collar 406 is lower end of a first vertical member 407 which is perpendicular disposed to shaft 402. The upper end of vertical member 407 is fixedly attached to the outer surface of an outer annular collar 408 of a

ball bearing assembly similar to the previously described ball bearing assembly; the components being an outer annular collar 408, ball bearings 410 (typical), and inner annular collar 409.

Slidesly retained within the central hole of inner annular collar 409 is a portion of a support drive shaft 411, said support drive shaft being in parallel disposition to aforesaid brush shaft 402. One end 411a of said support drive shaft 411 is centrally mounted at one end of motor M-2.

A second vertical member 416, similar to vertical member 407, and in parallel disposition therewith, is rotatably interconnected from support drive shaft 411 to connecting shaft 420, by means of ball bearing assemblies 460 and 461, respectively. Ball bearing assemblies 460 and 461 are similar to the aforesaid ball bearing assemblies in their construction and operation.

Mounted on said support drive shaft 411, between the end 411a thereof and motor M-2 are ball bearing assemblies, 413 and 414, similar to the aforesaid assemblies. Said ball bearing assemblies 413 and 414 are affixedly mounted to plates 413a and 414a, respectively; said plates, each in turn, straddle, interconnect and are affixedly mount to transversely disposed support bars 452 and 453, to be further discussed hereinafter.

Mounted within the inner annular collar of ball bearing assembly 461 is a rotatable connecting shaft 420 having on the inward end thereof a cup 421, the inner periphery of cup 421 receives one end 402b of square brush shaft 4102 by means of a ball and socket construction 470, similar to that shown in FIG. 3 hereof.

Thusly, the brush 401 is in parallel disposition to shafts 411 and 402 and joined thereto through vertical members 416 and 407, respectively, and through the aforesaid four ball bearing assemblies. Mounted to each of said vertical members, are hand grips 416a and 407a, respectively, so that a person in the bathtub can grip said hand grip. By this construction the brush may be manually positioned along an arcuate path, the radius of the arc being the length of the vertical members. In this manner the brush may by gripping the hand grips be positioned to several heights in the bathtub as is desired.

Referring to FIG. 12, there is shown the end 411a of support drive shaft 411 which shaft rotates with actuation of motor M-2. Mounted near the other end 411a is an upper pulley 424 having retained on the inner periphery of a central bore therein, an annular ring 425, said ring 425 frictionally held to drive shaft 411. The peripheral groove of upper pulley 424 frictionally receives endless belt 426.

Referring again to FIG. 12, there is shown the lower pulley 427, similarly constructed to the upper pulley 424, and having an inner annular ring 428, said ring frictionally receiving the aforesaid connecting shaft 420. The peripheral groove of the lower pulley frictionally receives the aforesaid endless belt 426 in a manner similar to that as afore-described for the upper pulley 424.

By this manner of construction, the actuated motor M-2 rotates drive shaft 411 causing rotation of upper pulley 424 thereby moving endless belt 426 which in turn translates its movement to lower pulley 427 which in turn causes rotation of connecting shaft 420 which

in turn rotates shaft 402 thereby rotating cylindrical brush 401.

The top side walls 404e and 404f of bathtub 404 are provided with guide channels 450e and 450f, respectively. The guide channels are pressedly held between walls W5 and W6 by turnbuckle means 451e and 451f are two sets of roller-mounted parallel, spaced, support bars 452 and 453 said bars in parallel disposition to shaft 411, and brush shaft 402; bar 452 having rollers 452a and 452b, freely rotatable thereon; and bar 453 having rollers 453a and 453b, freely rotatable thereon. The bars 452 and 453 per se do not rotate, but rotational bearing surfaces (not shown) permit free rotation of the rollers 452a, 452b, 453a and 453b. The 15 rollers upon rotation roll through and within aforesaid guide channels.

Guide channel 450f is provided with a slot 450g for receiving one end portion of support bars 452 and 453, so as to permit said bars to guidingly pass through said 20 slot. A motor support plate 490 transversely straddles and is affixed to at one end portion of bars 452 and 453. The motor M-2 is of course mounted to said plate 490. This manner of construction is preferred to that shown in FIGS. 4 and 5, insofar as the motor is not directly housed over the bathtub.

Still another distinct feature of the embodiment of FIGS. 11-14, is a protective housing 495, enclosed about the pulley and belt system as aforescribed. The housing is mounted on and slidably receives drive shaft 30 411 and connecting shaft 420.

The housing 495, protects a person in the bathtub from the rapid motion of the belt and pulley system.

A further feature of this embodiment is the addition of paddle wheels 498 and 499, slidably received on shaft 402 at opposite ends of brush 401. In operation, shaft 402 rotates and in turn rotates said paddle wheels so as to agitate the water in the bathtub, so as to provide additional therapeutic massaging action to a person in the bathtub. The paddles of the paddle wheels may be of any desired manner of configuration deemed suitable. The paddle wheels are of soft rubber material.

The mechanical operation of this embodiment of FIGS. 11-14 is similar to that of FIGS. 4-6.

It is to be understood that the forms of the invention hereabove shown and described are to be taken as preferred embodiments of the same and that resort may be had to various changes in construction without departing from the scope of the subjoined claims.

What is claimed is:

1. A bathtub brush device comprising a cylindrical brush adapted to be transversely disposed between side walls of a bathtub, means to rotatably mount said brush within said bathtub, and electric motor drive means to cause rotation of said brush, longitudinal guide means, a carriage, means to mount said carriage for back and forth movement relative to said guide means, said electric motor drive means comprising an electric drive motor on said carriage, said means to rotatably mount said brush comprising means to connect said brush for movement relative to the axis of said motor, and said drive means further comprising means driven by said motor to rotate said brush about the axis of said brush in various positions of said brush relative to the axis of said motor.

2. The device of claim 1, further comprising a bathtub, said bathtub comprising a pair of inner side walls

and a pair of outer side walls and two end walls, said cylindrical brush transversely disposed between said pair of inner side walls, and said guide means comprising a pair of guides mounted on the side walls of the bathtub.

3. The device of claim 2, said means to rotatably mount said cylindrical brush comprising a shaft axially disposed within said cylindrical brush and a pair of opposed shaft socket means, said each of said socket means fixedly housed within one of said inner walls, said each of said socket means slidably, rotatably receiving one end of said shaft.

4. The device of claim 3, said device further comprising a cup, spring means pressingly housed against the outer surface of said cup, the inside surface of said cup housing one end of said shaft, said spring means compressively retaining said shaft in said pair of socket means, said spring means permitting further compression thereof so as to permit axial movement of said brush so as to clear free the shaft end opposite to the direction of axial movement from the socket means therefor.

5. The device of claim 4, wherein said each of said socket means is fixedly mounted within one inner wall of said bathtub.

6. The device of claim 5, said shaft ends having a cross-section having at least two oppositely disposed flat surface and said each of said socket means having a cup for receiving one of said shaft ends, the configuration of the interior surface of said cup corresponding to the configuration of said shaft cross-section.

7. The device of claim 6, wherein said spring means is compressively housed between the inner surface of an outer wall and the outwardly facing outer surface of said cup.

8. The device of claim 7, wherein said outwardly facing outer surface of said cup is of spherical configuration.

9. The device of claim 1, said device further comprising switch means electrically connected to said drive motor for actuating said drive motor, said switch means fixedly mounted to the outer surface of one outer wall of said bathtub.

10. A bathtub brush device comprising in combination: a cylindrical brush transversely disposed between side inner walls of a bathtub, said bathtub comprising a pair of opposed side inner walls, side outer walls, opposed end walls and side top walls; means to rotatably mount said brush; connecting means connected to and for rotating said means to rotatably mount said brush; drive translating means interconnected to said connecting means, and interconnected to a drive shaft of drive means, said drive means comprising a drive motor and drive shaft, said drive shaft in parallel disposition above said means to rotatably mount said brush and said connecting means, said drive translating means perpendicularly disposed to said drive shaft and to said means to rotatably mount said brush and to said connecting means; a support shaft, said support shaft in parallel disposition above said connecting means and rotatable brush mounting means and in axial disposition to said drive shaft, said support shaft fixedly mounted to said drive means, said drive means mounted on a horizontally disposed plate and positioning means affixed to said plate, positioning means movably mounted to said side top walls to move along the length of the bathtub on said side top walls; a pair of parallel vertical mem-

bers, said each of said members having one rotational sleeve assembly fixedly attached to the lower end thereof and one rotational sleeve assembly fixedly attached to the upper end thereof; said one of said pair of vertical members being movably interconnected through the upper rotational sleeve assembly thereof to said support shaft and movably interconnected through the lower rotational sleeve assembly thereof to one end of means to rotatably mount said brush, the second of said vertical members being movably interconnected through the upper rotational sleeve assembly thereof to said drive shaft and movably interconnected through the lower rotational sleeve assembly to said connecting means; so that said vertical members are simultaneously swingable, and resultantly said brush is arcuately positionable about said drive shaft and said support shaft, to various heights within the tub.

11. The combination of claim 10, wherein said positioning means comprises a pair of parallel, fixedly spaced support bars transversely disposed above and across the bathtub, said bars comprising at the ends of each thereof freely rotatable roller means, said bathtub further comprising guide means along the side top walls, said roller means in rolling contact with said guide means, so that said device is positionable along the side length the bathtub.

12. The combination of claim 10, said drive translating means comprising an upper pulley, the hub of said pulley being coincident to and connected with said drive shaft, a lower pulley, the hub of said lower pulley, being coincident with connected to said connecting means and an endless belt frictionally and tautly held within the respective peripheral grooves of each of said pulleys so that rotational motion is translated from said upper pulley to said lower pulley.

13. The combination of claim 12, said connecting means comprising a shaft integrally formed with a cup, at the inward end of said shaft, said cup the interior surface thereof slidably receiving said means to rotatably mount said brush so as to be rotatable therewith, spring means disposed in said cup compressively fitting between the recessed wall of said cup and one end of rotatable mounting means for said brush, said shaft of said connecting means rotatably fitting in a lower rotational sleeve assembly, and the outwardly disposed end of said shaft of said connecting means affixed within the hub of said lower pulley.

14. A bathtub brush device comprising a cylindrical brush adapted to be transversely disposed between side walls of a bathtub, means to rotatably mount said brush within said bathtub and electric motor drive means to cause rotation of said brush, further comprising a bathtub, said bathtub comprising a pair of inner side walls and a pair of outer side walls and two end walls, said cylindrical brush transversely disposed between said pair of inner side walls and said guides being mounted on the side walls of the bathtub, wherein said drive means comprises a drive motor and a drive shaft, further comprising

means interconnected to said drive shaft and interconnected to said means to rotatably mount said brush, wherein said drive motor is fixedly mounted to a vertical plate mounted to a wall portion common to a side outer wall of said bathtub, below the floor supporting said bathtub, said drive shaft passing clearly through said outer wall portion, said drive means disposed between the inner surface of

said side outer wall and the opposed outer surface of the side inner wall.

15. The device of claim 14, said drive translating means comprising upper pulley, the hub of said upper pulley being coincident to and connected with said drive shaft, a lower pulley, the hub of said lower pulley being coincident with and connected to connecting means, said connecting means passing through said inner wall and thereat interconnect with said means to rotatably mount said brush.

16. The device of claim 1, said cylindrical brush comprising a hollow base cylinder having bristles affixed to the cylindrically curved surface thereof and having receiving means at each end thereof for slidably receiving an inwardly disposed shaft end of said means to rotatably mount said brush, and spring means disposed within said hollow of said cylinder, said spring means compressively urging at least one of said inwardly disposed shaft ends outwardly.

17. The device of claim 15, said cylindrical brush comprising a hollow base cylinder having bristles affixed to the cylindrically curved surface thereof and having receiving means at each end thereof for slidably receiving an inwardly disposed shaft end of said means to rotatably mount said brush, and spring means disposed within said hollow of said cylinder, said spring means compressively urging at least one of said inwardly disposed shaft ends outwardly.

18. The device of claim 5, said outer surface of said cup being of partial spherical configuration.

19. The combination of claim 1, said means to rotatably mount said brush comprising an axial shaft passing through said cylindrical brush, a pair of bearings at opposite ends of said brush, one end of said shaft being journaled in one of said bearings, a socket member journaled in the other of said bearing and slidably receiving the other end of said shaft and spring means to bias the shaft in one direction.

20. The combination of claim 1, said means to rotatably mount said cylindrical brush comprising means to mount said brush for axial movement and means to bias said cylindrical brush in an axial direction and means to disengage said brush from said mounting means.

21. A bathtub brush device comprising a cylindrical brush adapted to be transversely disposed between side walls of a bathtub, means to rotatably mount said brush within said bathtub, and electric motor drive means to cause rotation of said brush, further comprising at least one paddle wheel axially mounted on said means to rotatably mount said brush so as to be rotatable therewith.

22. The device of claim 10, further comprising at least one paddle wheel axially mounted on said means to rotatably mount said brush so as to be rotatable therewith.

23. The device of claim 22, comprising a pair of paddle wheels, each thereof being disposedly mounted on said means to rotatably mount said brush at opposite ends of said brush.

24. The device of claim 10, a pair of hand grip means, one each thereof being integrally mounted to one of said pair of vertical members so that a person in the bathtub grips said hand grip means for arcuate positioning of said brush.

25. The device of claim 10, further comprising a housing mounted on said drive shaft, said housing being enclosed about said drive translating means so as to protect a person in the bathtub from said drive translating means.

26. The combination of claim 1, said means for mounting said brush for movement, comprising a pair of spaced parallel members each having means for rotation about the axis of said motor and means for rotatably mounting said brush thereon for rotation of said brush about its axis.

27. The combination of claim 1, said carriage comprising a pair of parallel shafts, means to rigidly connect said shafts to each other, wheels on the ends of said pair of shafts rotatably received in said guide means, and means to mount said drive motor on said pair of parallel shafts.

28. The combination of claim 1, a bathtub to receive said brush, and means to attach said guide means to the bathtub.
